(57) **CLAIM**

I claim the ornamental design for a seat tag, as shown and described.

DESCRIPTION

FIG. 1 is a perspective view of a seat tag, showing my new design;

FIG. 2 is a front elevational view thereof;

FIG. 3 is a rear elevational view thereof;

FIG. 4 is a left elevational view thereof;

FIG. 5 is a right elevational view thereof;

FIG. 6 is a top view thereof;

FIG. 7 is a bottom view thereof;

FIG. 8 a perspective view of a seat tag shown in an environment of use; and,

FIG. 9 is a perspective view of a seat tag shown in an alternate environment of use.

The broken line portion of the figure drawings is included to show environment that forms no part of the claimed design.
